UNITED STATES PATENT OFFICE.

ERNST F. AUTENRIETH, OF NEW YORK, ASSIGNOR TO THE GLEN COVE MACHINE COMPANY, (LIMITED,) OF GREEN POINT, BROOKLYN, NEW YORK.

EXPANSION-PULLEY.

SPECIFICATION forming part of Letters Patent No. 393,602, dated November 27, 1888.

Application filed July 25, 1888. Serial No. 281,009. (No model.)

To all whom it may concern:

Be it known that I, ERNST F. AUTENRIETH, of the city and county of New York, in the State of New York, have invented a new and useful 5 Improvement in Expansion Pulleys, of which the following is a specification, reference being had to the accompanying drawings.

My invention relates to that class of expansion pulleys in which a series of segment-pieces 10 for forming portions of the periphery of a pulley are arranged on a face-plate, disk, hub, or center piece, which is or may be fixed to a shaft, and are caused to move simultaneously toward and from the said hub, center piece, or shaft 15 by the operation of a collar or hub fitted to slide on and turn with the same shaft and connected with the segments by a series of extension-rods.

I will now proceed to describe the improvement, and will afterward point out its novel 20 features in claims.

In the drawings, Figure 1 is an end view of a fully-extended expansion-pulley embodying my invention, and Fig. 2 is a similar view of 25 the same pulley in its most contracted condition. Fig. 3 is a plan or face view corresponding to Fig. 1, and Fig. 4 is a horizontal section on line *x x* of Fig. 2.

Like letters of reference indicate corresponding parts in all the figures.

A designates a fixed hub or center piece having attached to it a series of tangential arms, *B*, united by a rim, *a*, the said arms and rim constituting a face-plate. The said arms 35 are grooved or slotted to constitute tangential guides for a series of segment-pieces, *C*, which are fitted to their slots or grooves. These segment-pieces form portions of the periphery of a pulley, and are capable of sliding along the 40 said guides toward and from the hub or center piece, *A*.

D indicates a shaft, upon which the hub *A* may be fixed, and is represented as so fixed in the drawings.

E indicates a hub or collar concentric with and movable toward and from hub *A*, which collar or hub *E* is also represented as fitted to slide upon and turn with shaft *D*.

G designates extension-rods of a series pivotally connected with said segment-pieces *C* and said movable hub *E*, to move in planes

tangential to a circle concentric with said hubs *A* and *E*.

H H indicate lugs formed on and projecting from each segment *C*, and fitted to move in the corresponding guide slots *B B* of the face-plate or disk. Upon each of said segments or lugs is a wrist-pin, *b*.

c c indicate wrist-pins projecting radially from hub *E*, and the relative position of the hubs on the shaft and the direction of the slots or grooves or guides *B B* are such that each wrist-pin *c* is always parallel to the corresponding wrist-pin *b*, as is requisite and necessary in order to place thereon the several extension-rods *G*, by which said wrist-pins are connected.

The outer or working faces of the segment-pieces are formed concentric with the hub *A*, and are portions of a cylinder of a radius corresponding to an intermediate position of said segments between the extremes of expansion and contraction represented in Figs. 1 and 2. The segment-pieces move from and toward the center of hub or shaft on radial lines, thus preserving always their concentricity, and the several guides or guide grooves or slots *B B* are parallel with the respective radial lines upon which the segments move, and are consequently tangential to a circle concentric with said hubs. The radial wrist-pins of the sliding hub are at the same distance from the axial line as are the wrist-pins of the lugs, and consequently the central lines of the guide-slots are in the central plane of the movements 85 of the respective extension-rods. By this arrangement of the parts less force applied to the hub *E* will be required to sustain or counteract the pressure of a belt on the face of the segments when the pulley is in use, and 90 the said hub may be placed closer to the face-plate than if the extension-rods were arranged to move in lines or planes radial to the axis of the shaft. The segment-pieces are retained in the guide grooves or slots *B B* by plates *d* and 95 screws *e*.

f is a feather on the shaft *D*, fitting a groove in the sliding hub *E*, to prevent the hub from turning on the shaft.

The hub *E* may be operated and held in any 100 suitable manner—as, for example, by a shifter-rod, *g*, operating a forked bell-crank, *h*, piv-

noted at *i* and engaging the hub by pins *j*, and a strap, *k*, fitting into a grooved head, *l*, with which the hub *E* may be provided for the purpose.

5. What I claim as new, and desire to secure by Letters Patent, is—

1. The combination, with a fixed hub or center piece having a series of guides rigidly attached thereto and projecting tangentially therefrom, of a series of segment-pieces for forming portions of the periphery of a pulley and fitted to said guides, a hub or collar concentric with and movable toward and from said fixed hub, and a series of rods connected with said segment-pieces and said movable hub, to move in planes tangential to a circle concentric with said hubs, substantially as herein described.

2. The combination, with a face-plate and a series of tangentially-arranged guides formed thereon, and a series of segment-pieces fitted to slide along said guides, of a shaft upon which said face-plate is secured, a hub or collar fitted to turn with and slide upon said shaft toward and from said plate, and a series of rods pivotally connected with said segment-pieces and said movable hub or collar, to move in planes tangential to a circle concentric with said hub and shaft, substantially as herein specified.

ERNST F. AUTENRIETH.
